UNITED STATES PATENT OFFICE.

CHARLES E. WAREAM, OF CINCINNATI, AND DANA H. BENJAMIN, OF CLEVELAND HEIGHTS, OHIO, ASSIGNEES TO THE AMERICAN LAUNDRY MACHINERY COMPANY, OF NORWOOD, OHIO, A CORPORATION OF OHIO.

IRONING-MACHINE.

1,398,248.

Specification of Letters Patent. Patented Nov. 29, 1921.

Original application filed July 2, 1917, Serial No. 178,286. Divided and this application filed November 18, 1917. Serial No. 201,786.

To all whom it may concern:

Be it known that we, CHARLES E. WAREAM and DANA H. BENJAMIN, citizens of the United States, residing at Cincinnati and 5 Cleveland Heights, respectively, in the counties of Hamilton and Cuyahoga, respectively, and State of Ohio, have invented certain new and useful Improvements in Ironing-Machines, of which the following is a 10 specification.

This invention relates to ironing machines and more particularly to machines for ironing shirts.

One form of machine for ironing shirts 15 comprises an ironing member or chest which coöperates with an ironing board upon which the shirt is dressed, said board having a bosom receiving portion and carrying an adjustable neck band former curved to produce the proper contour of the neck band before ironing the shirt. The ironing board is usually so formed as to produce a transverse folding line in the yoke practically tangent to the back of the neck band, and this form 20 of shirt makes it difficult to iron what may be called the back corners of the yoke, to-wit, those portions of the yoke lying between the rear curved corners of the neck band and folding line in the yoke. These back 25 corners of the yoke are commonly ironed by back corner ironers, which heretofore have been adjusted by hand into position adjacent the expanded neck band former, so as to properly position them for the various sizes 30 of neck band operated upon by the machine.

The present invention has for its object 35 to provide an ironing machine whose back corner ironers do not require to be adjusted by hand, but are moved into proper ironing relation with the neck band former, in all adjusted positions of the latter, by the ordinary operation of the machine to produce ironing relation between the chest and board.

40 A further object of the invention is to provide a back corner ironer which is automatically adjusted into proper ironing position by the relative ironing movement of the bed and chest, and which back corner ironer 45 produces proper results regardless of the size to which the neck band former is adjusted.

Further objects of the invention are in

part obvious and in part will appear more in detail hereinafter.

The invention comprises the construction 55 and arrangement of parts hereinafter described and claimed.

In the drawings, which represent one embodiment of the invention, Figure 1 is a front elevation of one form of ironing machine 60 embodying the invention; Fig. 2 is a sectional plan view on the line 2—2 Fig. 11; Fig. 3 is a detail cross section on the line 3—3 Fig. 2; Fig. 4 is an elevation from the tail end of one of the ironing boards; Fig. 65 5 is a sectional elevation on the line 5—5 Fig. 1, looking in the direction of the arrows, parts being omitted; Fig. 6 is a cross section on the line 6—6 Fig. 5; Fig. 7 is a cross section on the line 7—7 Fig. 5; Fig. 8 is a detail 70 plan view of the neck band former; Fig. 9 is a longitudinal section thereof on the line 9—9 Fig. 8; Fig. 10 is a cross section on the line 10—10 Fig. 8, and Fig. 11 is a detail 75 view, partly in section, showing the operating mechanism for the back corner ironer.

This application is a division of our prior 80 application for ironing machine, filed July 2, 1917, Serial No. 178,286 to which reference may be had for a more complete description 85 of a machine embodying the invention. So far as illustration or description of said machine are required for the purpose of this case, it comprises a suitable frame 1 having an upright pillar 2 at one side and at its opposite side standards 3 which support a head 4 carrying the stationary ironing chest or member 5. Said chest is of common form, comprising a hollow metal member heated in any suitable manner, such as by steam circulated through its inner chamber 6 by means of the pipes 7. At one end of said chest is a recess 8 which registers with the neck band former of the board when the latter is brought into ironing relation with the 95 chest, as will hereinafter appear.

The pillar 2 supports on a vertical axis a rotatable turret or frame 9, each of whose two arms supports an ironing board. By rotation of said frame on the pillar either 100 of said boards may be moved from the dressing or loading position at the left in Fig. 1 to a position directly beneath the chest, as at the right in Fig. 1. Since both of the

boards are alike in all respects description of one will suffice for both.

Each arm of the frame 9 is formed as a hollow sleeve 10 to receive a post 11 depending from the base 12 of the board. Said base may also be provided with a depending pin or bar 13 sliding in an opening of a bracket 14 on the frame 9 and arranged to prevent rotation of the board on the frame 10. The base 12 is provided with upright webs 15 which carry a block 16 attached to the underside of a longitudinal bar 17 lying in a recess of the board beneath the padding 18 thereon. This bar extends from the 15 tail end of the board to a point near the neck band thereof, where it is provided with recesses to receive vertical pins 19 on which are sleeves 20 mounted in recesses in the stationary forward portion 21 of the neck band former. The sleeves can rise and fall with the ironing motion, so as to allow the neck band former to sink with the padding when ironing pressure is applied to the shirt, but the connections described absolutely prevent 25 any horizontal motion of member 21 relative to the swinging frame 9. Consequently, whenever the shirt board is brought into proper position beneath the ironing chest the curve of the front portion of the neck band former lies in proper registering relation 30 with the recess 8 of the chest.

The shirt board, indicated at 22, is attached to and carried by a hollow frame 23 having a base 24 sliding longitudinally on 35 V ways of the base 12 (see Fig. 7). At one end the board 22 carries a back yoke receiving member 25, from which rises a plate 26 having a head 27 provided with a recess or slot to receive a transversely extending rod 40 28 whose opposite ends enter openings in the adjustable back portions 29 of the neck band former. Said portions 29 are attached to rods or pins 30 which enter horizontal diagonally disposed openings in the stationary 45 forward portion 21 of the neck band former. When the frame 23 with the attached shirt board 22 is moved back the rod 28 is also carried back and moves with it the adjustable rear portions 29 of the neck band former, said portions moving from the full line to the dotted line position Fig. 8, and thereby expanding the neck band former, but substantially maintaining its shape or form and its registering relation with the 50 recess of the chest, and also preserving the tangent relation of the transverse end edge of the board to the back of the neck band former.

31 indicates a neck band clamping member, whose forward portion 32 is in the form 60 of an apron depending in front of the stationary front portion of the neck band former, and whose body portion slides longitudinally in a recess 33 of the neck band former. This clamping member is suitably con-

nected to a rod 34 carrying a spring 35 adapted to normally push the clamping device away from the neck band former. Rod 34 extends rearwardly through an opening in an L shaped member 36 and then through 70 a guiding opening in an upwardly extending portion 37 of a slide 38 movable longitudinally in the portion 21 of the neck band former and provided with a recess 39 to receive the lower edge of member 36. Between members 36 and 37 is located a light compression spring 40. The opening in member 36 is slightly larger in diameter than the rod 34, so that when the vertical portion of member 36 assumes a position 80 askew to the axis of rod 34 it grips the rod and prevents it from moving forwardly. Nevertheless, the clamping device can be pushed backwardly by pressure applied directly to its exposed portion, which oscillates member 36 about its lower edge and releases said rod 34 from the locking device.

Slide 38 is also provided with a depending notched portion 41 to receive an upwardly extending toe 42 on a bar 43 slidably mounted in a recess or channel of the bar 17, and whose forward end (see Fig. 5) is pivotally connected to one arm of a lever 44 whose other arm is pivotally connected to a rod 45. Said rod, when pulled forwardly, moves the clamping member 31 into firm clamping engagement with the neck band. The actuating means for said rod is as follows:

Web 15 of the stationary base 12 support a cross shaft 46 carrying a gear segment 47 and a cam 48. Segment 47 co-operates with a gear segment 49 rotating on a shaft 50 and carrying a depending arm 51 adapted to move between an abutment 52 of the movable frame 23 and a cross bar 53 carried thereby. A pin 54 extending laterally from the arm 51 engages the depending arm 55 of a pivoted lever whose other arm 56 carries a roller 57 lying beneath the horizontal arm 58 of a latch lever pivoted at 59 and provided with a depending arm 60 whose toe 61 lies at one side of rod 62. Rod 62 is attached to the cross bar 53 and extends 115 through guiding openings in frame member 63. Said toe 61 also lies in front of a locking member 64 having a base 65 seated in the frame, and which locking member surrounds the rod 62 and has an opening 120 slightly larger than said rod. This locking member is similar in operation to the member 36 before referred to and is moved to the right, or into locking engagement with the rod by a compression spring 66. Cam 125 48 lies opposite and co-operates with a roller 67 on the lower arm of a pivoted lever whose upper arm is pivotally connected to a sleeve 68 having sliding movement on the rod 45 and lying adjacent a compression spring 130

69 between said sleeve 68 and nuts 70 adjustably threaded on the end of said rod. Rod 45 is also provided with a collar 71 serving as a seat for one end of a compression spring 72, whose opposite end abuts the frame 23. Shaft 46 extends out through one of the webs 15 and on its outer end is provided with an operating handle or lever 73.

10 The shirt is dressed upon the board when lying in the loading position at the left in Fig. 1, with the neck band surrounding the neck band former, said former being in collapsed position. The clamping device 31 is pushed with the fingers into light clamping engagement with the neck band to temporarily hold the same. The operator then lifts the handle or lever 73 in Fig. 5. The first motion of said lever is an idle motion so far as the gear segment 49 is concerned, as the lever 51 is moved idly from abutment 53 to abutment 52. During this motion cam 48 moves the rod 45 to the right in Fig. 5 and through the spring 69 moves the clamping device 31 backwardly into powerful clamping engagement with the shirt neck band. Further upward motion of lever 73 causes the lever 51 to push back the frame 23, which carries back with it the board 22 and back yoke receiving member 25 and the rear portions 29 of the neck band former, thereby expanding said neck band former and filling the neck band of the shirt.

35 The shirt is now ready for ironing and the frame 9 is swung around to bring the dressed board into ironing relation with the ironing chest.

Upward movement of the board into ironing engagement with the chest may be produced in any suitable manner. The drawings show for this purpose a cylinder 73^a to which fluid pressure is admitted when desired to elevate its piston 74, and as the rod 75 of said piston lies beneath the post 11 the board is raised by fluid pressure.

Referring now to Figs. 2 and 5, 76 indicates two like back corner ironers which slide in or on guiding members 77 carried by the chest. The lines of movement of said back corner ironers diverge at the same angles and in the same directions as the rods 30 of the neck band former, and the inner ends of said back corner ironers are curved to correspond with the curvature of the rear portions 29 of the neck band former. These back corner ironers are movable as described in order to enable them to be adjusted inwardly into registering relation with the neck band former, whereby, when the chest and board come together, said back corner ironers iron those portions of the shirt lying between the curved rear portions of the neck band former and the folding line at the end of the board, and

this regardless of the size to which the neck band former may be adjusted. The actuating mechanism for the back corner ironers is as follows:

Each back corner ironer is pivotally connected to a link 78, the two links 78 being connected to the opposite arms of a yoke 79 whose central portion is pinned or otherwise connected to rotate with a cross shaft 80 on the head 4. One end of said shaft 75 carries an arm 81 connected by a clevis 82 to a rod 83 having slidably mounted thereon a sleeve 84. 85 represents a pressure spring lying between said sleeve and a collar 86 adjustably mounted on rod 83. Sleeve 84 is pivotally connected to an arm 87 on a shaft 88 provided within the head 4 with an arm 89 carrying an antifriction roller 90. 91 represents an abutment plate hinged at 92 at one side of the recess 8 of the chest 85 so as to be capable of being moved from the inoperative position shown in dotted lines, Fig. 2 to the full line operative position indicated in said view. In this position the abutment plate lies directly over the neck band former of the board, and said plate carries a slidably mounted vertical pin 93 whose lower end normally projects below the plate, and whose upper end lies beneath the roller 90.

Let us assume that the parts are in the position shown in Fig. 11, with the board moving upwardly into coöperating ironing engagement with the chest. As the board moves upwardly the stationary part of the neck band former finally engages the pin 93, thereby lifting the same. Upward motion of the pin oscillates the levers 87 and 81 and causes the back yoke ironers to move inwardly toward the neck band former. 105 When they engage the neck band of the shirt further upward motion of the neck band former is taken up by the compression spring 85. When the board finally reaches ironing relation with the chest the back corner ironers are in position to iron the back corners of the shirt and act in the same manner as other stationary portions of the chest. In other words they depress the padding of the board uniformly with depression of the padding at other parts of the board by the stationary portions of the chest. During the final upward movement of the board the neck band former contacts the abutment plate and itself may sink with 110 the padding.

When the board is retracted downwardly from the chest the parts return to their normal positions ready for another operation.

What we claim is:

1. An ironing machine, comprising a bed, a coöperating chest, said bed and chest being relatively movable, a neckband former, a back corner ironer movable into coöperat- 130

- ing relation with the neck band former, and means for producing said movement of the ironer simultaneously with relative approaching movement of the bed and chest.
- 5 2. An ironing machine, comprising a bed, a coöperating chest, said bed and chest being relatively movable, a neckband former, a back corner ironer movable into coöperating relation with the neckband former, an 10 automatic means actuated by operation of the machine for producing said ironer movement.
- 15 3. An ironing machine, comprising a bed, a coöperating chest, said bed and chest being relatively movable, a neckband former, a back corner ironer movable into coöperating relation with the neckband former, and means whereby the closing movement of the machine effects said ironer movement.
- 20 4. An ironing machine, comprising a bed, a coöperating chest having a recess, said bed and chest being relatively movable, a neckband former, a back corner ironer movable into coöperating relation with the neckband former, and means rendered effective by the 25 entry of said neckband former into said recess to produce said ironer movement.
- 30 5. An ironing machine, comprising a bed, a coöperating chest, said bed and chest being relatively movable, a neckband former, a back corner ironer movable horizontally toward and from said neck band former, and means whereby relative movement of said bed and chest produces movement of said 35 ironer.
- 40 6. An ironing machine, comprising a bed, a coöperating chest, said bed and chest being relatively movable, a neckband former, a back corner ironer on said chest movable into coöperative relation with the neckband former, and means whereby relative movement of said bed and chest produces said ironer movement.
- 45 7. An ironing machine, comprising a bed, a coöperating chest, said bed and chest being relatively movable, a neckband former, a back corner ironer carried by said chest and movable toward and from said neckband former, and means carried by the chest and 50 actuated by the bed for moving the ironer.
- 55 8. An ironing machine, comprising a bed, a coöperating chest, said bed and chest being relatively movable, a neckband former, a back corner ironer carried by said chest and movable toward and from said neckband former, and means whereby relative movement of said bed and chest produces movement of said ironer.
- 60 9. An ironing machine, comprising a bed, a coöperating chest, said bed and chest being relatively movable, a neckband former, a back corner ironer, and means for actuating said ironer by relative movement of said bed and chest, said means including an operating member for transmitting the rela-
- tive motion of said bed and chest to said ironer, said operating member being adjustable either to operative or inoperative position.
10. An ironing machine, comprising a bed, a coöperating chest, said bed and chest being relatively movable, a neckband former, a back corner ironer movable toward and from said neckband former, and means for actuating said ironer by relative approach 75 of the chest and neckband former, said means including an operating member for transmitting the relative motion of said bed and chest to said back corner ironer, said operating member being adjustable either to operative or inoperative position.
11. An ironing machine, comprising a bed, a coöperating chest, said bed and chest being relatively movable, a neckband former, a back corner ironer movably mounted on 80 said chest, and means for actuating said ironer by relative movement of said bed and chest, said means including an operating member for transmitting the relative motion of said bed and chest to said back corner ironer, said operating member being adjustable either to operative or inoperative position.
12. An ironing machine, comprising a bed, a coöperating chest, said bed and chest being relatively movable, a neckband former, a back corner ironer, and means for actuating said ironer by relative movement of said bed and chest, said means including an operating member for transmitting the relative 85 motion of said bed and chest to said back corner ironer, said operating member being adjustable either to operative or inoperative position.
13. An ironing machine, comprising a bed, a coöperating chest, said bed and chest being relatively movable, a neckband former, a back corner ironer, and means for actuating said ironer by relative movement of said bed and chest, said means including an operating member for transmitting the relative motion of said bed and chest to said back corner ironer, said operating member being adjustable either to operative or inoperative position, and in operative position engaging the neckband former to thereby depress it 90 on its bed when the bed and chest come together.
14. An ironing machine, comprising a bed member provided with an adjustable neckband former, means for adjusting said former to various sizes of neckband, a chest member including back corner ironing portions having movement toward and from the neckband and a bosom ironing portion provided with a neckband receiving recess, said bed and chest members being relatively movable for the ironing operation, and means whereby the relative movement of said members causes engaging relation between said back corner ironing portions and a neckband 100 on said former regardless of the size to which the former is adjusted.
15. An ironing machine, comprising a bed member provided with an adjustable neckband former, means for adjusting said former to various sizes of neckband, a chest member including back corner ironing portions having movement toward and from the neckband and a bosom ironing portion provided with a neckband receiving recess, said 105 bed and chest members being relatively movable for the ironing operation, and means whereby the relative movement of said members causes engaging relation between said back corner ironing portions and a neckband on said former regardless of the size to which the former is adjusted.
16. An ironing machine, comprising a bed member provided with an adjustable neckband former, means for adjusting said former to various sizes of neckband, a chest member including back corner ironing portions having movement toward and from the neckband and a bosom ironing portion provided with a neckband receiving recess, said 110 bed and chest members being relatively movable for the ironing operation, and means whereby the relative movement of said members causes engaging relation between said back corner ironing portions and a neckband on said former regardless of the size to which the former is adjusted.
17. An ironing machine, comprising a bed member provided with an adjustable neckband former, means for adjusting said former to various sizes of neckband, a chest member including back corner ironing portions having movement toward and from the neckband and a bosom ironing portion provided with a neckband receiving recess, said 115 bed and chest members being relatively movable for the ironing operation, and means whereby the relative movement of said members causes engaging relation between said back corner ironing portions and a neckband on said former regardless of the size to which the former is adjusted.
18. An ironing machine, comprising a bed member provided with an adjustable neckband former, means for adjusting said former to various sizes of neckband, a chest member including back corner ironing portions having movement toward and from the neckband and a bosom ironing portion provided with a neckband receiving recess, said 120 bed and chest members being relatively movable for the ironing operation, and means whereby the relative movement of said members causes engaging relation between said back corner ironing portions and a neckband on said former regardless of the size to which the former is adjusted.
19. An ironing machine, comprising a bed member provided with an adjustable neckband former, means for adjusting said former to various sizes of neckband, a chest member including back corner ironing portions having movement toward and from the neckband and a bosom ironing portion provided with a neckband receiving recess, said 125 bed and chest members being relatively movable for the ironing operation, and means whereby the relative movement of said members causes engaging relation between said back corner ironing portions and a neckband on said former regardless of the size to which the former is adjusted.
20. An ironing machine, comprising a bed member provided with an adjustable neckband former, means for adjusting said former to various sizes of neckband, a chest member including back corner ironing portions having movement toward and from the neckband and a bosom ironing portion provided with a neckband receiving recess, said 130 bed and chest members being relatively movable for the ironing operation, and means whereby the relative movement of said members causes engaging relation between said back corner ironing portions and a neckband on said former regardless of the size to which the former is adjusted.

- bed and chest members being relatively movable for the ironing operation, actuating means for producing such relative movement, and means affected by operation of 5 said actuating means for automatically moving said back corner ironing portions into engagement with a neckband on said former regardless of the size to which said former is adjusted.
- 10 15. An ironing machine, comprising a bed member provided with an adjustable neckband former, a coöperating chest member having a recess adapted to register with the neck band former, means for adjusting said 15 neckband former to various sizes of neckbands and maintaining its registering relation with said recess throughout its range of adjustment, back corner ironers movable relatively to said neckband former, mechanism 20 for actuating said bed and chest members for the ironing operation, and means operated thereby for causing engaging relation between the back corner ironers and a neckband on said former regardless of the 25 size to which the former is adjusted.
16. An ironing machine, comprising a bed member provided with an adjustable neckband former having a relatively stationary front portion and back portions movable
- rearwardly with the bed and with respect to 30 said stationary front portion, a chest member having a recess adapted to register with the stationary front portion of the neck band former, operating means for the back portions of said neck band former, back corner 35 ironers movable into coöperating relation with the back portions of a neckband on said former, and actuating mechanism therefor, the arrangement being such that operation of said operating means does not disturb 40 either the registering relation between the neckband former and recess in the chest or the coöperating relation between the back corner ironers and the back portions of the neckband.
17. An ironing machine, comprising relatively movable bed and chest members, a neckband former on the bed, an ironing member movable into coöperating relation with the neck band former and actuated by 45 relative movement of the bed and chest members, and adjustable means for rendering 50 said ironing member operative or inoperative.

In testimony whereof we affix our signatures.

CHARLES E. WAREAM.
DANA H. BENJAMIN.
